UNITED STATES PATENT OFFICE.

CHARLES E. ARCHER AND EDWARD C. HUMPHREYS, OF DETROIT, MICHIGAN.

SIGNAL-LAMP.

1,309,392.

Specification of Letters Patent.

Patented July 8, 1919.

Application filed June 6, 1918. Serial No. 238,468.

To all whom it may concern:

Be it known that we, CHARLES E. ARCHER and EDWARD C. HUMPHREYS, citizens of the United States of America, residing at Detroit, in the county of Wayne and State of Michigan, have invented certain new and useful Improvements in Signal-Lamps, of which the following is a specification, reference being had therein to the accompanying drawings.

This invention relates to signal lamps and may be considered an improvement over those lamps disclosed by our Patents Nos. 1,259,824; 1,259,823; 1,259,867; 1,259,822, all granted March 19, 1918, and Patent No. 1,262,799, granted April 16, 1918, particularly Patent No. 1,259,824, showing a dirigible lamp having universal movement so that light rays may be projected in various directions.

The present invention aims to provide a signal lamp having a universal movement and which may be easily and quickly manipulated with one hand for signaling purposes, the lamp being applicable to air planes and other crafts where it is necessary that a signal lamp be adjustable in all directions and capable of manipulation with one hand, so that an aviator may also attend to other duties while signaling.

Our invention further aims to provide a signal lamp having various adjustments with novel locking means for maintaining the lamp in an adjusted position, and provision is made so that the light or illuminating medium within the lamp may be flashed or controlled in any position to which the lamp is set. This is essential during aerial reconnoitering or scouting duty in order that the lamp carrying air craft may signal to other air craft or to land observers irrespective of the position of the signaling air craft.

Our invention will be hereinafter considered and reference will now be had to the drawing, wherein—

Figure 1 is a side elevation of the signal lamp partly broken away and partly in longitudinal section;

Fig. 2 is a cross sectional view taken on the line II—II of Fig. 1;

Fig. 3 is a similar view taken on the line III—III of Fig. 1;

Fig. 4 is a cross sectional view of a portion of the operating mechanism showing the preferred form of a flexible power transmission member;

Fig. 5 is a plan of the lamp;

Fig. 6 is a cross sectional view taken on the line VI—VI of Fig. 1;

Fig. 7 is a similar view taken on the line VII—VII of Fig. 1;

Fig. 8 is a side elevation of a portion of the signal lamp, partly broken away and partly in section, illustrating a modification of our invention;

Fig. 9 is a cross sectional view taken on the line IX—IX of Fig. 8, and

Fig. 10 is a plan of a portion of a locking device forming part of the modified form of lamp.

In the drawings, the reference numeral 1 denotes a support which may be one of the struts of an air-plane, a portion of the fuselage or any other part of the craft where the lamp may be supported convenient to the aviator or observer in the air plane. Suitably connected to the support is a bracket 2 terminating in a barrel or tubular member 3.

4 denotes a tubular arm fixed in the barrel 3, as at 5, said arm having the outer end thereof provided with a hollow cylindrical head 6 into which extends the reduced end 7 of a hollow cylindrical yoke head 8.

9 and 10 denote sets of tubular or hollow yoke arms having the outer ends thereof provided with adjustable casings 11 and 12 respectively, disposed in opposed relation.

13 denotes a lamp housing having a detachable reflector 14 provided with an incandescent lamp 15, and said housing has diametrically opposed trunnions or gudgeons rotatable on sleeve portions 17 of the casings 11 and 12.

18 denotes a tubular shaft journaled in the arm 4 and having the outer end thereof integral with the reduced end 7 of the yoke head 8, while the inner end of said tubular shaft is provided with a nut 19 that prevents longitudinal displacement of said tubular shaft relative to the arm 4 and the head 6.

20 denotes an inner toothed clutch member slidable on the inner end of the tubular shaft 18 and held, as at 21, for rotation therewith, said inner clutch member having a cylindrical casing 22 inclosing a pin head 23 fixed on the inner end of the tubular arm 4. The casing 22 has a series of circumferentially disposed apertures adapted to receive pins 24 carried by the head 23 and the pin head 23 and casing 22 are normally in-

terlocked by the pressure or expansive force of a spring 25 disposed within the casing 22 and bearing against the pin head 23.

26 denotes a tubular handle shaft journal in the shaft 18 of the yoke head 8 and slidably on the inner end of the yoke shaft 26 is a handle 27 having the ends thereof provided with outer clutch members 28 and 29, the former being adapted for interlocking engagement with the inner clutch member 20, when the handle 27 is shifted toward the casing 22. With the clutch members 20 and 28 interlocked, the handle 28 may be shifted on the shaft 26 to shift the apertured casing 22 out of engagement with the stationary pin head 23, and then the handle 27 may be partially rotated in either direction so as to turn the yoke head shaft 18 and turn the lamp about the axis of the handle shaft. It is therefore possible to oscillate or wig-wag the lamp or lock it in an adjusted position through the medium of the pin head 23 and the casing 22, constituting locking means for holding the yoke in an adjusted position relative to the head 6 of the arm 4.

30 denotes a grooved or notched wheel in the yoke head 8 and fixed for rotation with the outer end of the handle shaft 26. It is preferable to have the wheel notched, as shown in Fig. 4, but it may have a peripheral groove as shown in Figs. 1 and 2. Trained about the wheel 30 is a flexible power transmission member 31 that may be in the form of a chain, as shown in Fig. 4, or in the form of a cable as shown in Figs. 1 and 2, said member extending through the yoke arm 9 and trained about a grooved or notched wheel 32 in the casing 11. The wheel 32 is mounted on a stud 33 extending through the sleeve portion 17 of the casing 11 and fixed relative to the trunnion or gudgeon 16 of the lamp housing 13. The casings 11 and 12 are made adjustable on the ends of the sets of yoke arms 9 and 10 so as to take up any lost motion in the power transmission member 31.

34 denotes an inner clutch member on the inner end of the handle shaft 26, and with the outer clutch member 29 interlocked with the inner clutch member 34 by shifting the handle 27, the handle may be partially rotated to impart a similar movement to the handle shaft 26, which through the medium of the wheels 30 and 32, and power transmission member 31, adjust the lamp housing 13 in the yoke. It is therefore possible to oscillate or wig-wag the lamp or lock it in an adjusted position through the medium of the pin head 23 and the casing 22 constituting locking means for holding the yoke in adjusted position relative to the head 6 of the arm 4. By oscillating the handle 27 the lamp housing 13 may be wigwagged or turned in a desired direction relative to its supporting yoke, and the various movements

may be accomplished by simply shifting the handle 27 longitudinally of the shaft 26 and turning it in the desired direction.

35 denotes a detachable closure plate for the outer end of the cylindrical yoke head 8 and the inner face of said plate is provided with a block of insulation 36 having pins 37 adapted to extend into a series of circumferentially disposed openings or apertures 38 in the side of the wheel 30. A spring 39 maintains the wheel 30 normally in engagement with the pins 37, said pins and the block of insulation 36 serving as a pin head somewhat similar to the pin head 33, and constituting means for locking the handle 27 against accidental rotation. Besides placing the handle 27 in interlocked engagement with the shaft 26 to rotate the same, it is necessary to shift the shaft 26 longitudinally of the yoke shaft in order to move the wheel 30 out of engagement with the pins 37.

Considering now the electrical connections and the control for the incandescent lamp 15, said connections and controlling mechanism are disposed so as to prevent short circuits and not interfere with the universal movement of the lamp.

40 denotes an insulator in the sleeve portion 17 of the casing 12 and extending through said insulator are leading-in wires 41 to the incandescent lamp 15, said wires extending between the wall of the housing 13 and the wall of the reflector 14. The outer ends of the lead-in wires 41 are connected to insulated disks 42 and normally engaging said disks are brushes 43 supported by an insulator 44. The casings 11 and 12 have detachable side plates 45 so that the parts within said casings can be readily assembled.

46 and 47 denote conductors connected to the brushes 43 and extending through one of the yoke arms 10, the conductor 46 being connected to a binding post 48 supported by 110 and insulated from the reduced end 7 of the yoke head 8. The conductor 47 extends to the block of insulation 36 and is connected to a resilient switch member 49 movable to and from a stationary switch member 50, 115 carried by the block of insulation. The stationary switch member 50 is connected by a conductor 51 to a binding post 52 on the end of the head 8.

53 denotes an insulator in the head 6 of the arm 4, and on that face of the insulator confronting the reduced end 7 of the yoke head 8 are concentric rings 54 and 55. These rings are engaged by brushes 56 carried by the binding posts 48 and 52, and the rings 54 and 55 have binding posts 57 for lead-in wires 58. The wires 58 extend through a suitable insulator 59 in the head 6 and are adapted to be connected to a suitable source of electrical energy (not shown).

60 denotes a reciprocable switch rod concentrically of the handle shaft 26, the wheel 30 and the inner clutch member 34, said switch rod having the outer end thereof normally engaging the resilient member 49. The inner end of the switch rod has a cylindrical enlargement 61 in the clutch member 34 and there is a pin and bayonet slot connection 62 between the clutch member 34 and enlargement 61 so that the switch rod 60 can be locked in adjusted position. The enlargement 61 has a knurled knob or handle 63 so that it may be easily rotated and reciprocated, and a pin 64 in the switch rod 60 prevents accidental withdrawal of the switch rod from the handle shaft 26.

It is now apparent that through the medium of the disks, rings, brushes, switch and conductors that the incandescent lamp 15 may be continuously illuminated or flashed, irrespective of the position of the lamp and during any adjustuent thereof. A band gripping the handle 27 can easily and quickly make desired adjustments, and at the same time control the illumination of the lamp.

Reference will now be had to Figs. 8 to 10 inclusive, illustrating a modified form of signal lamp, and more particularly the locking mechanism for controlling the oscillation of the lamp in its yoke.

66 and 67 denote casings similar to the casings 11 and 12 of the preferred form of construction and in this modified form we place a portion of the lamp actuating mechanism and a portion of the electrical connections in the casing 67. In other words, we combine the elements 32, 33, 40, 42 and 43 of the preferred form of construction with 40 in the casing 67, use one of the arms 10 for the power transmission member, and the other of said arms 10 for the conductors 46 and 47. This leaves the casing 63 and the set of arms 9 so that we may install the 45 modified form of locking device.

68 denotes a trunnion or a gudgeon of the lamp 13 and said trunnion extends into the casing 66 and is provided with a toothed wheel 69. Engaging the toothed wheel 69 50 is a spring pressed latch or detent 70 pivoted within the casing 66 and connected to the end of a cable or flexible rod 71 that extends through one of the tubular yoke arms 9 into the yoke head 8. In the yoke head 8 the 55 cable or rod 71 is connected to an angular crank 72 on the outer end of the switch rod 60 and said crank is adapted to be sprung over a lug 73 on a retaining washer 74 mounted in the yoke head 8. The retaining washer 74 is notched, as at 75, so as to facilitate assembling the elements within the yoke head 8, and with the crank 72 sprung over the lug 73, the latch or detent 70 is held in a retracted position, thus permitting of the 65 lamp housing 13 being freely adjusted. By

partially turning or rocking the switch rod 60, the latch or detent 70 may be released to engage the toothed wheel 69 and hold the lamp in an adjusted position.

While in the drawings there are illustrated 70 the preferred embodiments of our invention it is to be understood that the structural elements are susceptible to such variations and modifications as fall within the scope of the appended claims. 75

What we claim is:—

1. A signal lamp comprising an arm, a yoke at the outer end thereof held for rotation about the axis of said arm, a lamp trunnioned in said yoke, a handle at the inner end of said arm adapted to be reciprocated in one direction and rotated to effect a movement of said yoke and reciprocated in the opposite direction and rotated to effect a movement of said lamp on its trunnions, and 80 a switch at said yoke operatable from said handle and adapted for controlling the illumination of said lamp.

2. A signal lamp comprising an arm, a yoke at the outer end thereof held for rotation about the axis of said arm, a lamp carried by said yoke, shiftable means at the inner end of said arm adapted for effecting a movement of either said yoke or said lamp, means in the inner end of said arm adapted 95 to hold said yoke against movement during the operation of said lamp, and means at the outer end of said arm adapted to hold said lamp against movement during the operation of said yoke. 100

3. A signal lamp comprising a hollow yoke, a lamp trunnioned between the arms of said yoke, means extending through one of the arms of the yoke and adapted for shifting said lamp in said yoke, means extending through the other arm of said yoke adapted for conducting an electric current to said lamp, and means in said yoke adapted to lock said lamp shifting means. 105

4. A signal lamp comprising an arm, a yoke at the outer end thereof held for rotation about the axis of said arm, a lamp carried by said yoke, a yoke shaft journaled in said arm, locking means for said yoke shaft, a shaft journaled in said yoke shaft and adapted for imparting movement to said lamp, locking means in said yoke for the last mentioned shaft, and reciprocable means on the last mentioned shaft adapted to release either of said locking means and adapted for imparting movement to either of said shafts. 115

5. A signal lamp comprising an arm, a yoke at the outer end thereof held for rotation about the axis of said arm, a lamp trunnioned in said yoke, a shaft in said arm adapted for imparting movement to said yoke, a shaft in said arm adapted for imparting movement to said lamp, and means reciprocable on the lamp actuating shaft 125 130

adapted to establish an operating connection with either of said shafts.

6. A signal lamp comprising an arm, a yoke at the outer end thereof held for rotation about the axis of said arm, a lamp trunnioned in said yoke, a shaft in said arm adapted for imparting movement to said yoke, a shaft in said arm adapted for imparting movement to said lamp, a handle reciprocable on the lamp actuating shaft and adapted to be operatively connected to either of said shafts, and means mounted concentrically of said handle adapted for controlling the illumination of said lamp during any adjustment thereof.

7. A signal lamp comprising an arm, a yoke at the outer end thereof held for rotation

about the axis of said arm, a lamp carried by said yoke, concentric shafts journaled in said arm and adapted for imparting movement to said yoke and said lamp, reciprocable means on one of said shafts adapted to be operatively connected to either of said shafts for imparting movement thereto, and locking means at the ends of said shafts adapted for holding said shafts against accidental movement.

In testimony whereof we affix our signatures in presence of two witnesses.

CHARLES E. ARCHER.

EDWARD C. HUMPHREYS.
